UNITED STATES PATENT OFFICE

STEADMAN O. TAYLOR, OF ST. LOUIS, MISSOURI, ASSIGNOR TO T & S CORPORATION, OF CHICAGO, ILLINOIS, A CORPORATION OF ILLINOIS

FASTENING DEVICE

Original application filed May 25, 1928, Serial No. 280,548. Divided and this application filed May 20, 1930. Serial No. 453,966.

This invention relates to fastening devices and more particularly to cotter pins and means for automatically locking the same in position.

5 The principal object of the invention is the provision of new and improved means for spreading the arms of a cotter pin in applying the same in use.

10 Another object of the invention is the provision of a new and improved cotter pin together with novel means for spreading the arms of the same laterally at right angles to the plane of the arms of the pin.

15 A further object of the invention is the provision of a new and improved cotter pin together with novel means for spreading the arms of the same, that is simple in construction, inexpensive to manufacture and efficient in use.

20 Other and further objects and advantages of the invention will appear from the following description taken in connection with the accompanying drawings, in which

25 Fig. 1 is an elevation of a cotter pin showing the invention in position therein;

Fig. 2 is a similar view at right angles to that shown in Fig. 1;

Fig. 3 is a section on line 3—3 of Fig. 2;

30 Fig. 4 is a perspective view of a modified form of spreader member;

Fig. 5 is a similar view of a further modified form of spreader member;

Fig. 6 is an elevation of a blank from which the structure shown in Fig. 5 is formed;

35 Fig. 7 is an elevation of a portion of a cotter pin showing a still further modified form of spreader member in position therein; and

Fig. 8 is a perspective view of a portion of the spreader member shown in Fig. 7.

40 Referring now to the drawings, the reference character 10 designates a cotter pin which may be formed in the usual manner from half round wire bent back on itself to form the eye 11 and the arms 12 and 13. The ends of the arms 12 and 13 are provided with oppositely arranged diagonal faces 14 and 15 so arranged as to form a V-shaped recess 16 at the outer ends of said arms. Preferably this recess is formed by cutting one

of the arms diagonally in one direction and the other in the other direction as shown in Fig. 1 of the drawings. A suitable spreader member 17, see Fig. 4, is provided for distorting the ends of the arms.

45 The spreader member 17 comprises a thin, flat body portion 18 having laterally extending wings 19 at one end thereof. The wings 19 may be bent as shown at 21 and 22 in Fig. 3 to prevent lateral movement of the inner 50 end of the body portion when the same is in position between the arms of the pin.

The outer end of the spreader member 18 is provided with suitable means for engaging the inclined faces 14 and 15. As shown, the 55 outer end of the body portion 18 is provided with an enlarged portion 23 having on one side the inclined or diagonally arranged face 24 and on its opposite side a corresponding inclined face 25 arranged to extend in 60 the opposite direction from that of the face 24. When the parts are in assembled relation as shown in Fig. 1 the body portion 18 is between the arms of the pin and the inclined face 24 is in engagement with the inclined face 15, and the inclined face 25 is in 65 engagement with the inclined face 14, of said arms.

70 In use, the pin is inserted in an opening in a bolt or the like and is struck on its inner end with one or more blows of a hammer which will cause the arms to be distorted laterally at right angles to the plane of said arms. The spring pressure of the arms will grip the body portion of the spreader for 75 preventing longitudinal movement of the spreader during the shipment of the device and the enlarged portion 23 engaging in the V-shaped groove 16 will prevent lateral movement of the outer end of the spreader member while the bends 21 and 22 will prevent the lateral movement of the inner end of the spreader member.

80 The construction shown in Fig. 5 differs 85 from that just described in that the head or enlarged outer end 26 of the spreader member 27 is formed from sheet metal. The blank for forming the spreader member is shown in Fig. 6 and comprises the flat, thin body portion 28, the laterally extending 90

wings 29 and 31 on the inner end of said member. The outer end of the member is provided with laterally extending wings 32 and 33. These wings are provided with inclined edges 34 and 35. These wings are bent over on to the body portion 28, one on one side and the other on the other side. The inclined edges 34 and 35 will correspond to the inclined edges 24 and 25 of the device 10 described above.

The form of construction shown in Figs. 7 and 8 differs from the construction previously described in that the head 36 of the spreader member 37 is not provided with inclined surfaces for engaging the corresponding inclined surfaces 14 and 15 of the cotter pin 10. In this form of construction the spreader member is made from a strip of metal, the inner end being formed with wings 20 as described above and its outer end or head 36 being formed by bending the same at right angles to the body portion 38. The head 36 is adapted to engage in the V-shaped groove 16 and when the pin is forced in an opening 25 of a bolt or the like the head 36 will engage the inclined surfaces 14 and 15 and bend the arms laterally as in the previously described construction.

This is a division of my application Serial 30 No. 280,548 filed May 25, 1928, for fastening device, now Patent 1,768,721, July 1, 1930.

I claim as my invention:

1. In combination, a cotter pin having a pair of arms provided at their outer ends 35 with beveled edges, said edges extending in a plane at an angle to the plane of said arms and forming a V-shaped recess, the planes of said edges intersecting in a line extending in the plane of said arms, a spreader pin having 40 a flat body portion located between said arms and having a shoulder extending laterally from its inner end, a head having inclined surfaces for engaging the beveled edges of said V-shaped recess for spreading said arms 45 in a plane parallel with the plane of said body portion, said inclined surfaces extending across said flat body portion.

2. A spreader member comprising a flat body portion, a shoulder extending laterally 50 from one end of said body portion, the opposite end of said body portion being provided with inclined surfaces which intersect the surfaces of said body portion in lines extending diagonally across said body portion.

3. In combination, a cotter pin comprising a length of wire bent back on itself to form a pair of arms, the outer ends of said arms being beveled diagonally in a plane arranged 60 at an angle to the plane of said arms, the planes of said beveled surfaces intersecting each other in a line extending in the plane of said arms, and a spreader member between said arms and having a laterally extending 65 shoulder at one of its ends and a pair of

inclined surfaces extending across opposite faces of said body portion and engaging the beveled surfaces of said arms for bending said arms in planes at right angles to the plane of said arms.

4. A spreader member formed from sheet metal comprising a body portion, a projection extending laterally from one end thereof, a pair of wings having inclined edges on the opposite end of said body portion, said wings being folded over on opposite sides of said body portion.

In testimony whereof I affix my signature.

STEADMAN O. TAYLOR.
